UNITED STATES PATENT OFFICE.

FRED W. COOLEY, OF MINNEAPOLIS, MINNESOTA, ASSIGNOR OF TWO-THIRDS TO GEORGE T. HONSTAIN, OF SAME PLACE.

FIREPROOF GRAIN-ELEVATOR.

SPECIFICATION forming part of Letters Patent No. 683,443, dated October 1, 1901.

Application filed April 9, 1901. Serial No. 54,969. (No model.)

To all whom it may concern:

Be it known that I, FRED W. COOLEY, (whose post-office address is 313 South Third street, Minneapolis, Minnesota,) a citizen of 5 the United States, residing at Minneapolis, in the county of Hennepin and State of Minnesota, have invented certain new and useful Improvements in Fireproof Grain-Elevators; and I do hereby declare the following 10 to be a full, clear, and exact description of the invention, such as will enable others skilled in the art to which it appertains to make and use the same.

My present invention relates to the construction of fireproof elevators or grain-storage bins or similar buildings, and has for its object to improve the same in the several particulars hereinafter noted.

My said present invention is on the same 20 general line of fireproof structure as that set forth in my prior United States application, Serial No. 47,541, filed February 16, 1901, and application, Serial No. 50,557, filed March 11, 1901, both entitled "Fireproof grain-elevators."

My present invention is directed chiefly to an improved form of joint or corner connection for uniting the corners of the bins and the metal framework at the corners of the 30 bins. It is also directed to the general construction of the building, whereby relatively small bins are made to brace and reinforce a relatively large interior bin, which is surrounded thereby.

35 The invention is illustrated in the accompanying drawings, wherein like characters indicate like parts throughout the several views.

Figure 1 is a diagram showing a plan or a 40 horizontal section of a grain-elevator designed in accordance with my invention. Fig. 2 is a detail in horizontal section, illustrating the construction of one of the joints marked *a* in Fig. 1, the said section being

45 taken on the line $x^2 x^2$ of Fig. 3. Fig. 3 is a vertical section on the line $x^3 x^3$ of Fig. 2. Fig. 4 is a horizontal section through one of the joints marked *b* in Fig. 1, said section being taken on the line $x^4 x^4$ of Fig. 5. Fig. 50 5 is a vertical section on the line $x^5 x^5$ of Fig. 4. Fig. 6 is a detail in vertical section on the line

$x^6 x^6$, Fig. 4. Fig. 7 is a horizontal section illustrating a slightly-modified construction of the joint *a*, said section being taken on the line $x^7 x^7$ of Fig. 8. Fig. 8 is a vertical section on the line $x^8 x^8$ of Fig. 7. Fig. 9 is a plan view showing in detail the form of coupling-link used in the joints indicated at *a* in Fig. 1 and shown in detail in Figs. 2 and 3. Fig. 10 illustrates the form of coupling-link used in 60 the joints marked *b* in Fig. 1 and illustrated in detail in Figs. 4, 5, and 6, and Fig. 11 is a plan view showing in detail the form of coupling-link used in the joint illustrated in Figs. 7 and 8.

65 In the construction illustrated in this case, as in my prior applications above identified, the walls of the building or bins are built up of layers of tile-blocks, between which layers are interposed horizontally-extended I-beams afforded by channel-strips laid back to back. The said tile-blocks are indicated by the numeral 1. The channels which constitute the I-beams are indicated by the numeral 2, and as shown and preferred, the flanges of the 70 said beams are bent inward, so that when cement *z* is applied between the same and the edges of the tile-blocks embraced thereby, as best indicated in Fig. 6, the said tile-blocks and beams will be cemented together 75 by a dovetail joint. The bottoms and tops of the layers of tile-blocks are faced with strips of thin metal 3, which close the openings in the tile-blocks and adapt certain of the same to be filled with concrete or cement, 80 as presently described.

85 In accordance with my present invention I employ in the corners of the bins hollow corner-tiles 4, which are preferably square in cross-section. Between the corner-tiles 90 4 I place rectangular coupling-links of metal, preferably steel, which links have square perforations corresponding in size to the size of the square passages through the corner-tiles 4.

95 The form of coupling-link used in the joints *a* and illustrated in Figs. 2, 3, and 9 is indicated by the numeral 5, and, as best shown in Fig. 9, the same is of simple rectangular form, having a rectangular perforation.

The form of coupling-link used in the

joints *b* and illustrated in Figs. 4, 5, 6, and 10 is indicated as an entirety by the numeral 6. This coupling-link 6 is provided at one side with a perforated tail extension 6^a and 5 at its other side with a heavy lug or ear 6^b.

The form of coupling-link used in the construction illustrated in Figs. 7 and 8 is very similar to that shown in Fig. 9, except that its outer dimensions are larger. The said 10 link is indicated as an entirety by the numeral 7.

Returning now to the construction of the joint *a* illustrated in Figs. 2 and 3, it will be noted that the flanges of the channel-beams 15 2 are cut away at the outer edges of the coupling-links 5 and that the extended or flat body portions 2^a of coöperating beams 2 are extended between overlying pairs of said links 5 and then are turned vertically, one 20 upward and the other downward, through said links 5 and against the interior walls of the corner-tiles 4. The cavities of the corner-tiles 4 are then filled with concrete or cement, as indicated at *z'*, and when this cement 25 hardens the parts are interlocked and become practically an integral mass. At the same time solid and very strong columns are formed at the corners of the bins. *z²* indicates cement placed between the tile-blocks 30 1 and 4.

The joint *b* (illustrated in Figs. 4, 5, and 6) connects three abutting walls, the two alined walls of which, in fact, constitute a single wall for the large interior bin. The 35 third wall, which extends at a right angle thereto, serves as an abutment to prevent the long wall of the said large internal bin from being bulged out. To still further strengthen the said walls of the large bin, tie-rods *f* are 40 employed.

The tie-rods *f* are pivotally connected with *f'* by suitable bolts, rivets, or other devices to the inwardly-projecting lugs 6^b of the coupling-links 6. As shown in Figs. 4 and 5, the 45 flat webs of the channel-beams 2 are extended inward as far as the ends of the lugs 6^b, and the said lugs are provided with reinforcing-plates 6^c, bolted or otherwise secured thereto. The tail extension 6^a of the coupling-links 6 are extended under several of the cells or cavities of the overlying and underlying tile-blocks, and anchor-pins 8 are passed therethrough and through the webs of the channel-beams 2 and through the metal strips 50 3. Cement or concrete (indicated at *z³*) is then placed in the cells of the tile-blocks, so as to securely set or anchor the pins 8. The ends or webs of the channel-beams 2, which are used in the alined wall-sections, are turned 55 into and cemented within the corner-tiles 4 the same as in the joint *a* above described.

With the above-described construction it will be noted that a continuous chain of metal sections extending from one extremity to the 60 other of the building are afforded by a connected series of channel-beams 2, coupling-links 6, and rod or rods *f*.

With the construction above described the walls of the large interior bins are made very strong, so that very large interior bins may 70 be used with safety.

Where very strong columns are required at the corners of the bins or on a bin, as when the said columns are called upon to support a cupola or tower, the construction illustrated 75 in Figs. 7 and 8 may be employed. This construction is very similar to that illustrated in Figs. 2 and 3; but in this construction supplemental corner tile-blocks 9 are laid upon the corners of the large coupling-links 7, and 80 anchor-pins 10 are extended through said links 7 and the webs of the channel-beams 2. Cement or concrete *z⁴* is then filled into the cells of the tile-blocks 1, surrounding the said anchor-pins 10. The corner tile-blocks 9 may 85 also be filled with cement or concrete, as indicated at *z⁵*. *z⁶* indicates cement used to cement together the tile-blocks 1, 4, and 9.

It will of course be understood that the construction above described is capable of many 90 modifications not herein specifically set forth without departing from the spirit of my invention.

What I claim, and desire to secure by Letters Patent of the United States, is as follows: 95

1. In a building of the character described, the combination with successive layers of tile-blocks of interposed metal beams, and corner-tiles into which the ends of said metal beams are projected and secured by cement 100 or similar filling material, substantially as described.

2. In a building of the character described, the combination with layers of wall-tiles and corner-tiles, of metal coupling-links interposed between said corner-tiles, and metal beams interposed between the layers of wall-tiles and projecting into and interlocking 105 with said coupling-links and corner-tiles, and cement or similar material filling the said corner-tiles and rigidly interlocking the parts, 110 substantially as described.

3. In a building of the character described, the combination with layers of wall-tiles and hollow corner-tiles, of metal coupling-links 115 interposed between said corner-tiles, flanged metal beams interposed between the layers of wall-tiles, the ends of the same extending through said coupling-links and bent against the walls of said corner-tiles, and cement or 120 similar material filling said corner-tiles and rigidly interlocking the parts, substantially as described.

4. In a building of the character described, the combination with successive layers of 125 wall-tiles and corner-tiles, of a pair of metal coupling-links placed between each pair of corner-tiles, and a pair of channel-beams extended between adjacent layers of wall-tiles with the flanges cut from their ends, and 130 these ends turned, one upward and the other downward, through said coupling-links and against the interior walls of corner-tiles, and cement filling said corner-tiles and rigidly in-

terlocking the parts, substantially as described.

5. A building of the character described, comprising a relatively large interior bin, or 5 compartment, and relatively small outer bins, surrounding and reinforcing the same with certain of the walls of said outer bins arranged to act as abutments for the intermediate portions of the walls of said large 10 interior bins, and tie-rods connecting opposite abutment-forming walls, substantially as described.

6. A building of the character described, made up of layers of tile-blocks and inter- 15 posed metal beams, arranged to form a relatively large interior bin and a plurality of relatively small outer bins surrounding and reinforcing said interior bin with certain of their walls forming abutments for the walls 20 of said interior bin, and metal tie-rods connecting the metal beams of opposite abutment-forming walls, substantially as described.

7. In a building of the character described, 25 the combination with successive layers of wall-tiles and corner-tiles, of I-beams interposed between certain of the layers of tiles, which I-beams are made up of channel-beams, laid back to back, and the ends of which are

bent, the one upward and the other down- 30 ward, within the cavities of the corner-tiles, and cement filling the cavities of the corner-tiles and rigidly interlocking the parts, substantially as described.

8. In a building of the character described, 35 the combination with successive layers of wall-tiles and corner-tiles, of interposed metal beams, each made up of a pair of channel-beams laid back to back, and the ends of which are turned, the one upward and the 40 other downward, within the said corner-tiles and are interlocked therewith, substantially as described.

9. In a building of the character described, 45 the combination with layers of wall-tiles and corner-tiles, of metal links interposed between said corner-tiles, and metal beams interposed between the layers of wall-tiles and projecting into and interlocking with said coupling-links and corner-tiles, substantially 50 as described.

In testimony whereof I affix my signature in presence of two witnesses.

FRED W. COOLEY.
